UNITED STATES PATENT OFFICE.

JOHN FREDERICH PLATH, OF MAZA, NORTH DAKOTA.

BROODER.

1,257,023.

Specification of Letters Patent. Patented Feb. 19, 1918.

Application filed November 28, 1917. Serial No. 204,398.

To all whom it may concern:

Be it known that I, JOHN FREDERICH PLATH, a citizen of the United States, residing at Mazza, in the county of Towner and State of North Dakota, have invented a new and useful Brooder; and I do hereby declare the following to be a full, clear, and exact description of the invention, such as will enable others skilled in the art to which it applies to make and use the same.

This invention relates to an improved brooder, particularly adapted for raising incubator chickens.

One of the objects of the invention is to provide an improved brooder in which the hovering means is so arranged as to prevent the chickens from gathering or crowding in the corners of the casing of the brooder.

A further object of the invention is to provide hovering means carrying members, which are easily detachable and removable by opening the lid or cover of the brooder casing, thereby permitting access to the interior thereof for cleaning purposes and the like.

A further object of the invention is to provide improved hovering means (consisting of soft feathers) which is arranged spirally, thereby permitting the chickens to nestle thereunder in a manner more in accord with or similar to the nestling under the feathers of a mother chicken or hen.

A further object of the invention is to provide hovering means carrying members consisting of frames over which pieces of textile fabric, preferably are stretched and secured, and to which pieces of fabric the hovering means or feathers are sewed or stitched or otherwise fastened.

A further object of the invention is the provision of textile fabric pieces to which the hovering means is attached and whereby the heat in the brooder chamber may slowly penetrate and enter into a chamber above the hovering means carrying members and from which chamber above said members the heat may pass out through one or more holes or perforations of the side walls of the casing of the brooder. The perforations are not exceedingly large, hence there is no way for the heat to escape very rapidly. Therefore, in this manner, the heat in the brooder chamber is maintained more or less uniform.

However, by opening the lid or cover of the brooder casing more or less, as the case may be, the heat in the upper chamber may pass out more or less rapidly thereby more or less moderating the heat in the brooder chamber.

A further object of the invention is the provision of a brooder having a heat chamber centrally of the brooder chamber, said heat chamber having laterally extending outlet tubes or passages which extend through the uppermost chamber.

A further object of the invention is the provision of means whereby the heater for the heat chamber may be adjusted vertically.

A further object of the invention is the provision of improved means for attaching the hovering means to the textile fabric pieces of the hovering means carrying members.

In practical fields, the details of construction may necessitate alterations falling within the scope of what is claimed.

The invention comprises further features and combination of parts, as hereinafter set forth, shown in the drawings and claimed.

In the drawings:—

Fig. 1 is a view in perspective of the improved brooder constructed in accordance with the invention.

Fig. 2 is a view in perspective of the brooder showing the lid or cover open.

Fig. 3 is a sectional view on line 3—3 of Fig. 1.

Fig. 4 is a sectional view on line 4—4 of Fig. 1.

Fig. 5 is a detail perspective view of a portion of the textile fabric of the hovering means carrying members, showing how the hovering means or feathers are fastened spirally thereto.

Fig. 6 is a bottom plan view of the structure shown in Fig. 5 more clearly showing the spiral arrangement of the hovering means.

Fig. 7 is a detail sectional view of the means for attaching the hovering means or feathers to the textile fabric of the hovering means carrying members.

Referring more especially to the drawings, 1 designates a suitable brooder casing, which is mounted upon conventional form of legs 2, and which may be constructed of any suitable material, preferably wood

and may be any suitable shape, preferably rectangular. The casing is provided with a lid or cover 3 connected to the casing by the hinges 4, there being a hook and eye 5 fastener 5 for holding the lid or cover closed. Two of the opposite sides of the casing on their inner faces are provided with upstanding cleats, acting as supports 6. In the corners of the interiors of the 10 brooder casing, cleat supports 7 are arranged. The bottom of the brooder is provided with an enlarged opening 8, and rising upwardly from the bottom adjacent the marginal edge of the opening is a suitable metallic cylindrical casing 9, the interior 15 of which constitutes a heat chamber 10. Extending from and communicating with the interior of the casing, at diametrically opposite points, are tubes or pipes 11, which 20 extend toward and are secured in the sides of the brooder casing having the cleats or supports 6, whereby the heat from the heat chamber may gradually pass off to the atmosphere. Secured to the underface of the 25 bottom of the brooder casing by means of screws 12 is an angular bracket 13, the depending part 14 of which is provided with elongated openings or slots 15. A suitable shelf 16 is provided for the support of the 30 heater or lamp 17, there being a depression 18 in the shelf for the reception of the fuel receptacle 19 of the heater. The shelf 16 is provided with an extension hook 20, which extends into any one of the openings 1 or 35 slots 15. This extension hook 20 has an upturned abutment 21, which, when the extension hook is in engagement with one of said openings or slots, abuts one face of the bracket, thereby supporting the shelf and 40 the heater or lamp thereon. Hovering means carrying members 22 are provided, and are designed to engage the upper ends of the cleat supports, 6 and 7. Each member 22 consists of a rectangular frame, to which 45 a piece of textile fabric 23 is secured, as shown at 24. The adjacent rails or longitudinal parts 25 of the frames 22 are provided with semi-circular cutaway portions 26 to engage about the upper portion of the 50 cylindrical wall of the casing 9, as shown in Fig. 2 clearly. By virtue of the hovering means carrying members, the brooder casing is divided into a brooder chamber 27 and an upper chamber 28, into which the 55 heat from the brooder chamber may gradually pass by penetrating through the textile fabric pieces 23. One of the walls of the brooder casing is provided with one or more apertures or openings 29, through which 60 the heat from the chamber 28 may slowly pass, hence lessening the heat in the chamber 28, and allowing the heat in the brooder chamber to become more or less uniform or moderated, according to the amount of heat

radiating from the wall of the heat chamber. The cover or lid of the casing may be propped open in various positions, in order to allow the heat from the chamber 28 to pass off, to more or less moderate the heat in the brooder chamber. In this manner the 65 heat in the brooder chamber may be lessened or decreased more rapidly. Depending from the textile fabric pieces 23 are hovering means 30, each of which consists of hanging or depending feathers 31. In order to 70 fasten or attach the feathers of the hovering means to the textile fabric pieces 23, textile fabric strips 32 are folded longitudinally upon themselves, and between the folded parts, the larger ends of the quills of 75 the feathers are stitched or otherwise fastened, as at 33. The folded strips adjacent their folds 34 are secured by stitches 35 to the fabric pieces 23, and are arranged spirally, and extended outwardly and down- 80 ly, so as to hold the hovering means or feathers in spiral form, as shown in Figs. 5, 6 and 7, clearly. By this spiral arrangement of the hovering means or feathers, the 85 young chickens are allowed to nestle there- 90 under and in the passages 36 more similar to nestling under the feathers of a hen. Two of the opposite walls of the brooder chamber are provided with sight openings 37, which are provided with coverings of 95 some suitable transparent material, preferably celluloid or mica 38. The lid or cover of the brooder casing may be supported entirely open by means of suitable chain 39, as shown in Figs. 2 and 4. The brooder 100 casing is provided with an opening 40, upwardly to which a tread board 41 is inclined, whereby the chickens may enter the brooder chamber, there being a suitable hinged door 42 having a latch for closing 105 the opening 40.

The invention having been set forth, what is claimed as new and useful, is:—

1. In a brooder, a hovering means carrying member consisting of a rectangular frame and a piece of flexible textile fabric stretched thereover, spirally arranged hovering means consisting of feathers depending downwardly from the textile fabric piece and a piece of textile fabric folded 110 longitudinally upon itself with the quills of the feathers between the folds and stitched to the first textile fabric piece for securing the feathers thereto.
2. In a brooder, a casing, removable hovering means carrying members dividing said casing into a brooder chamber and a superimposed chamber into which the heat of the brooder chamber may first pass prior to passing off to the atmosphere, said second chamber having exit openings for the heat, heating means for the two chambers and being centrally disposed with relation to 115
3. In a brooder, a hovering means carrying member consisting of a rectangular frame and a piece of flexible textile fabric stretched thereover, spirally arranged hovering means consisting of feathers depending downwardly from the textile fabric piece and a piece of textile fabric folded 120 longitudinally upon itself with the quills of the feathers between the folds and stitched to the first textile fabric piece for securing the feathers thereto.
4. In a brooder, a casing, removable hovering means carrying members dividing said casing into a brooder chamber and a superimposed chamber into which the heat of the brooder chamber may first pass prior to passing off to the atmosphere, said second chamber having exit openings for the heat, heating means for the two chambers and being centrally disposed with relation to 125

both chambers, said members having textile fabric pieces through which the heat from the heater chamber may penetrate to enter the superimposed chamber, and spirally arranged hovering means depending from the textile fabric pieces, said members having semi-circular cutaway portions to engage about the heating means.

In testimony whereof I have signed my name to this specification in the presence 10 of two subscribing witnesses.

JOHN FREDERICH PLATH.
